CLOTHES DRIER DEVICE

Otto Bahls, Brooklyn, N. Y.

Application January 6, 1949, Serial No. 69,453

1 Claim. (Cl. 211—119.07)

1

This invention relates to a clothes drier device. The invention has for its object to provide a simple device which may be easily applied to a window frame, or removed therefrom, consists of a few simple parts, and is inexpensive to make.

In the proposals heretofore made, the devices were rather complex, were difficult to make, were cumbersome, and most of them were rather expensive. Many had inherent defects, which rendered their continued use troublesome.

This invention is based fundamentally on the spring action of a pulley supporting member, which spring action works to press upon brackets in either in or out position of the member in respect to the window frame, and which member is fixedly held in either in or out position, the member being capable of being removed by merely pressing the arms of the member towards each other against the spring action of the member. Simple line holders and brackets complete the commercial assemblage.

The invention will be further described hereinafter, an embodiment shown in the drawings, and the invention will be finally pointed out in the claim.

In the accompanying drawings,

Fig. 1 is a side view of the improved device applied to a window frame, with the holder inside of a room for the application of the articles to be dried;

Fig. 2 is a view partly in section taken from line 2—2 of Fig. 1;

Fig. 3 is a horizontal section taken on line 3—3 of Fig. 1;

Fig. 4 is a vertical section taken on line 4—4 of Fig. 3; and

Fig. 5 is a side view of the improved device showing it outside of the window.

Similar characters of reference indicate corresponding parts throughout the various views.

Referring to the drawings, and particularly to Fig. 1, the improved device is of the utmost simplicity. A pair of supports or brackets 10 are attached by screws or the like, 11, to the frame 12 of a window. These brackets 10 are vertically aligned. Each consists of a vertical member 13 with holes 14 for attaching screws 15, and of a horizontal member 16 at right angles thereto. At least one of these has two parallel projections 17 and 18, and an opening 19. The horizontal member 16 along the opening 19 is slightly bevelled as at 20. Each vertical projection 17 and 18 is slightly bevelled at its inner wall as at 21, and also is rounded or bevelled at its ends, as at 22. The upper of these brackets may

2

or may be like the lower one. The advantage of making the brackets identical is that it simplifies the sale of the equipment.

Similarly, identical loops 30 on screws 31, are provided to be attached to the window frame in vertical alignment, each for the passage of the rope or wash line 31. A pair of these loops 30 are arranged between the pair of brackets, as shown, in vertical alignment therewith. The loops 30 are formed by bending a metal rod or the like into a loop form, with an open entry and exit space 33.

In this environment, the improved pulley holder 40, is placed. This consists of a single metal rod bent into a helical spring portion 41, to give resiliency to the arms 43 and 44, each of which has an end 45, bent outwardly, in one case forming an upwardly directed member 46 and in the other case forming a downwardly directed member 47. Each of these members, 46 and 47, has a diameter slightly less than the diameter of the opening 19 in each bracket member. Before the holder 40 is applied to the brackets, it is necessary to move the arms 43 and 44 towards each other, and then after registering the bent ends 45 with the openings 19, permit the resilient action of the spring portion 41 to press the ends 45 to their original position, whereby a slight pressure is exerted by the arms 43 against the brackets.

When the holder is in one position (Fig. 1), the arms 43 and 44 are seated between the two projections 17 and 18, and thereby securely held in that position. (In my U. S. Patent No. 2,478,450 of August 9, 1949, for improvements in a Clothes Line Holder, I show and describe a similar device.) When the holder is in its other position (Fig. 5), again the ends 45 are seated between the projections 17 and 18, and thereby securely held in that position. The flaring parts 21, and the rounded portions facilitate the movement of the holder from one position to the other. When the arms 43 and 44 ride on the projections 17 and 18, the arms move towards each other, without the ends 45 escaping from the opening 19, and this yielding action enables an easy riding of the arms on the projections. For safety sake, cotter pins 47 are passed through suitable holes in the ends 45.

The line 31 passes over a pulley 48 having a hook 49 engaging the spring loop 41 of the holder. In Fig. 1, which corresponds to the position of the holder when the holder is inside of the room 55 for the ready application of the article to be

dried, the line 31 passes over the pulley, first being supported by the upper loop 30, and then the line again passes outside of the window being free while the clothes are being attached by clothes pins, or the like. When the clothes have been applied, the lower part of the line 31 is looped to the lower loop as shown in Fig. 5, and the holder is moved to its outside of the window position, the inherent spring pressure of the holder always exerting its pressure against the brackets. The arms 43 and 44 as shown in the drawings form an isosceles triangle with the vertical wall of the window frame as a base, having the spring portion at its apex, the line pull being along the median of said apex angle, whereby the arms resist substantially equally the line pull, when said member is in either position, within or without said window frame.

The parts are extremely simple in construction and number, and may be made at a low expense, and may be readily applied to a window frame outside of the window.

From the foregoing it is seen that the invention consists of a clothes drier device, comprising a single metal rod bent to a central convolution and to proximate position to each other and having outwardly bent ends, and a pair of brackets adapted to be secured to a window frame in vertical alignment and spaced from each a distance less than the distance between the arms contiguous to said bent ends, said brackets having openings engageable by said bent ends, the engagement of the arms with the brackets subjecting the arms to tension and exerting a pressure on said brackets. One of said brackets has means to hold the arms in either window in or window out position, and increases said tension. Said arms move from one of said positions to the other, said tension being released in either position, the tension being further increased before the arms can be removed from the brackets.

I wish it to be understood that I do not desire to be limited to the exact details of construction shown and described, for obvious modifications will occur to a person skilled in the art.

I claim:

In a clothes drier device for application to window frames having a pair of vertically aligned brackets spaced apart along a vertical wall of said window frame with each bracket having an opening, and at least one of said brackets having

a channel the longitudinal axis of which is aligned from the front to the rear of said window frame, and having a clothes drying line with a pulley for the window end of said line, said pulley having a hook, and a pair of line guides on said wall each adjacent one of said brackets, a pulley supporting member including the combination of a helical spring portion forming an eye adapted to be engaged by said pulley hook, with two arms 10 substantially of equal length extending integrally from said spring portion in divergent directions at either side of said eye, and vertically disposed end portions on said arms adapted to fit into said openings of said brackets, the normal spacing of 15 said ends being larger than the distance between the parts of said brackets facing each other requiring said ends to be moved towards each other to permit the entrance of said ends into said openings of the brackets at the facing parts 20 thereof by tensioning said spring portion, its expansion forcing the said ends into said bracket openings and pressing said arms against the facing parts of said brackets, and when said member is in its position within or without said window 25 frame, one of said arms engages said channel of said bracket to hold the member in one of said positions, said arms when engaging said brackets forming a substantially isosceles triangle with said vertical wall, as a base, and said spring portion at its apex, said arms resisting substantially 30 equally the line pull on said pulley along a median of said apex angle, when said member is in either position within or without the said window frame.

OTTO BAHLS.
